UNITED STATES PATENT OFFICE.

WILLIAM P. BROWN, OF LONDON, ONTARIO, CANADA.

FURNACE.

1,184,819.

Specification of Letters Patent. Patented May 30, 1916.

Application filed April 12, 1915. Serial No. 20,728.

To all whom it may concern:

Be it known that I, WILLIAM P. BROWN, a citizen of the Dominion of Canada, and resident of the city of London, in the Province of Ontario and Dominion of Canada, have invented certain new and useful Improvements in Furnaces, of which the following is a full, clear, and exact description.

This invention relates to improvements in furnaces of all descriptions, and the object is to provide means for burning certain of the products of combustion which usually escape in the form of flue gases.

A further object is to provide means for supplying additional oxygen to the fire for the purpose of preventing in some measure the escape of combustible gases to a region beyond the fire.

It is well known that in the combustion of fuel, the two principal gases formed are carbon monoxid and carbon dioxid, the former of which is readily combinable with oxygen, that is to say, combustible, while the latter is not combinable with oxygen and is therefore incombustible, and furthermore, cannot by any ordinary means be decomposed to yield a combustible gas. The monoxid is a lighter gas than the dioxid, and therefore readily separates from the dioxid. With these facts in mind, the device forming the subject of this invention has been produced, and comprises essentially means for separating the carbon monoxid and carbon dioxid in a furnace and collecting the monoxid, which is then discharged with sufficient oxygen for combustion into the zone of incandescent gases immediately above the fire, so that combination of the monoxid and oxygen takes place with an evolution of heat. The same means may be proportioned to discharge into the fire considerable oxygen in excess of that required to consume the collected monoxid, so that combustion of the fuel is carried on more perfectly than usual and the production of carbon monoxid in a measure prevented.

In the drawings which illustrate the invention, and show its application to a steam boiler furnace:—Figure 1 is a longitudinal section of a flue or fire tube boiler furnace. Fig. 2 is a similar view of a water tube boiler furnace. Fig. 3 is a section on the line 3—3, Fig. 1.

Referring more particularly to the drawings, 11 designates a boiler of the flue or fire tube type, mounted above a furnace 12

having the usual ash pit 13 through which air enters for combustion of the fuel. The flame and gases pass rearwardly under the boiler through a combustion chamber 14 60 and return forwardly through the boiler flues 15 to the smoke box 16, and thence to the smoke stack 17. At the rear end of the boiler is the usual passage 18 connecting the combustion chamber with the rear ends of 65 the boiler flues. In the present invention, this chamber is somewhat enlarged and extended upwardly a suitable distance above the uppermost row of flues to form a separating chamber 19, which is provided with 70 a domed or arched top 20. Flues 21 of refractory material are formed along the sides of the combustion chamber and furnace, extending from the rear of the boiler setting, where they are open to the atmosphere, to 75 the front of the furnace. Throughout the length of the furnace, these flues are provided with ducts 22 arranged to direct fluid jets transversely across the furnace above the fuel. A pipe 23 leads from the uppermost part of the separating chamber and extends downwardly and enters each flue 21, the pipe being turned forwardly and continued within the flue for a suitable distance. The pipe is sufficiently smaller than 80 the bore of the flue to leave an annular space 24 between the tube and flue walls for the passage of air, entering the open end of the flue. A damper 25 is provided in the smoke 85 stack. 90

The only difference between the structures shown in Figs. 1 and 2 are the differences incident to the furnaces themselves, and not to the present invention. In the furnace of a water tube boiler, the stack outlet, designated 17^a, is at the rear. The separating chamber 19 is in the same position as previously described, that is, above the outlet path of the gases. It will be understood that the invention is not limited to 95 the particular dimension and disposition of this separating chamber, providing the same is located above the outlet to the stack. 100

The operation of the device may be easily understood if it is borne in mind that the combustible carbon monoxid is lighter than the incombustible carbon dioxid, and will therefore rise to the highest point of the furnace, which in the present invention is the separating chamber 19, while the heavier 105 carbon dioxid follows the line of chimney draft and escapes from the furnace. The 110

carbon monoxid thus collected is led through the pipes 23 into the flues 21, where it is mixed with air and discharged into the furnace above the fire through the ducts 22 and burned. The flame produced is intensely hot. Passage of the monoxid downwardly through the pipe 23 is insured by the chimney draft. Air flow through the ash pit into the furnace is considerably restricted 5 by reason of the layer of fuel on the grates, whereas the flow of air through the flue 21 and ducts 22 is entirely free. This flow of air through the restricted annular passage 24 creates a strong suction in the pipe 23, 10 which combined with the upward pressure of the hot gases in the bottom of the chamber 19, carries the gas down through the pipe 23 into the flue 21. It will be noted 15 that this invention is dependent entirely upon the chimney draft for its operation, and not upon any artificially produced air currents. Therefore, the flow of air and monoxid will always be in proportion to the chimney draft and the condition of the fire without necessitating constant adjustment, as would be the case with an artificially produced air circulation. It will also be seen that this free draft through the flue 21 will greatly reduce the draft through the 20 grates, so that the furnace becomes essentially a surface burner, so that the breaking up and distillation of a large part of the fuel at each firing is to a great extent prevented. Carbon monoxid will inevitably be formed, 25 but instead of being carried up the smoke stack, this gas is separated from the incom- bustible dioxid and returned to the furnace, where it is burned with a great evolution of heat. The flame and air curtain above the fuel thus formed has the effect of burning a 30 large proportion of the small carbon particles which give the color to smoke.

Experiments have proven that a furnace equipped with this invention and with the ash pit doors closed and flue damper nearly 45 closed, will give better results and show a remarkable increase of efficiency over the same furnace, without the invention but with maximum draft through the ash pit.

It will be understood that the invention 50 is not limited to the particular type of boiler or other furnaces shown, but may be applied to any type of furnace, the essential features being a free suction of air into the sides of the furnace by the chimney draft, 55 inducing a supply of the combustible products of combustion collected in a chamber above the furnace outlet to the chimney.

Having thus described my invention, what I claim is:—

In combination in a furnace having a grate, a smoke outlet, a fire box, a gas collecting and separating chamber located within the furnace at a point higher than the smoke outlet and out of and above the 65 direct line of draft from the fire box to the smoke opening, said chamber being so positioned above said outlet that the lighter gases of combustion will rise therein and stagnate whereupon the gases of different 70 densities will separate naturally and means for conducting the lightest gas back to the fire box comprising an air inlet flue on the side of the fire box above the grate pro- 75 vided with openings communicating with the fire box and a return flue from said chamber terminating in said air inlet flue and encircled thereby.

In witness whereof, I have hereunto set my hand, in the presence of two witnesses. 80

WILLIAM P. BROWN.
